MOP WRINGER

Frank M. Fritsch and Lawrence B. Fritsch, Hamilton, Ohio, assignors to The Eagle Woodenware Manufacturing Company, Hamilton, Ohio, a corporation of Ohio

Application September 9, 1941, Serial No. 410,193

1 Claim. (Cl. 15—262)

This invention relates to improvements in a mop wringer.

An object of the invention is to provide in a mop wringer structure, improved and simplified means for protecting the wringer mechanism against entanglement with mop strands during the wringing operation.

Another object of the invention is to provide mechanism of the character stated, which is so constructed as to reduce friction between the parts to a minimum, with the result that little effort is required in performing the wringing operation.

Another object is that of constructing a wringer mechanism for application to a pail or other container, in such manner as to gain elevation of the wringer mechanism relative to the pail or container bottom, thereby to render available a maximum amount of space and a high level of liquid within the pail or container.

Further objects of the invention are to strengthen the pail or container through the medium of the wringer mechanism; to simplify the manufacture of parts and the assembly of the wringer mechanism; and to impart a high degree of durability and efficiency to the wringer mechanism.

The foregoing and other objects are attained by the means described herein and disclosed in the accompanying drawing, in which:

Fig. 1 is a perspective view of the improved mop wringing apparatus of the invention.

Fig. 2 is a small scale plan view looking down on Fig. 1, the container being shown in broken lines.

Fig. 3 is a perspective view of a modification.

With reference to the accompanying drawing, the character 4 indicates a mop bucket or other container, which may be of wood, metal or other suitable construction. The container has an open top through which a mop may be introduced, as is customary. When the container is of wood construction suitable hoops 5 may be applied thereto for maintaining the constituent staves in position to render the container fluid tight. The container may be provided near its bottom, with a lug or extension 6 upon which the operator may stand with one foot, while actuating the wringing mechanism with the other foot, this being customary practice in the use of such apparatus.

At opposite sides of the container are fixedly mounted the brackets 7 carrying stud shafts 8 which provide pivotal mountings for a foot treadle 9 to be depressed by means of the oper-

ator's foot, and rotated about the pivots against the resistance of a suitable spring 10. The spring may be so arranged as to operate upon one of the upright arms 12, tending always to rotate the arms of the treadle in counterclockwise direction, that is, in a direction such as to retract the shiftable squeezing roller 13 away from the cooperative squeezing rollers 14 and 15. The squeezing rollers 14 and 15 collectively may be considered a cooperative squeezing element or assembly adapted to coact with the shiftable roller 13 in wringing water or other fluid from a mop introduced between them.

It may here be stated that the term "cooperative squeezing element," in its broadest sense, may include any suitable form of stationary surface or surfaces, or a single roller such as 14 or its equivalent, as well as the pair of rotating rollers indicated at 14 and 15. Fig. 3 shows a modification of the invention wherein the cooperative squeezing element corresponding to that of Fig. 1, is in the form of a single roller mounted for rotation, but fixed in its relationship to the container.

In the preferred embodiment of the invention, the upright arms 12—12 are made integral with the treadle indicated at 9, and at the upper ends of said arms are formed, preferably by bending, the inwardly turned portions 16—16 and the downwardly turned ears or termini 17—17. The ears or terminal portions are pendent from the parts 16, so as to project toward the bottom of the container, and each is provided with an aperture or other bearing element 18 adapted to receive the shaft ends 19 of the shiftable roller 13, thereby to furnish a mounting permitting rotation of the roller, and also a swinging movement thereof along an arc toward and from the cooperative squeezing means 14—15. The opposite ends of the squeezing roller may be capped with metal or other suitable material to impart a finished appearance thereto, and for the further purpose of preventing splitting of the rollers when they are constructed of wood. The rollers, of course, may be made of metal, rubber, composition, or any other material suitable for the purpose for which they are intended.

If desired, braces 20 may be welded, riveted or otherwise suitably secured in spanning relationship to the upright arms and the treadle member, to strengthen the structure and to insure it against distortion in use.

Particular attention is directed to the mop guard rails 21—22, which span the open top of the container at opposite sides of a diameter, and

which are spaced apart in substantial parallelism a distance less than the length of the working face or pressing area of the shiftable roller 13. This relationship of parts may most clearly be seen in the Fig. 2 illustration of the drawing. The mop guard rails may have opposite ends 23 and 24 turned at an angle such as to rest flatwise against the concave inner surface of the container, against which the ends may be fixedly secured by means of bolts, rivets, or other fasteners 25. In the case of a container constructed of metal, welding or soldering, or equivalent means might also be resorted to in effecting the mounting.

From the disclosure of Fig. 2, it will readily be appreciated that the strands of a mop introduced into the space between the rollers 13 and 14, and between the mop guard rails 21 and 22 cannot possibly become entangled with the axle ends of the rollers. Moreover, since the shiftable squeezing roller 13 has no operative connection with the mop guard rails 21 and 22, there is precluded all possibility of mop strands interfering with the free shifting of roller 13 toward and from the roller or cooperative squeezing element 14. As previously stated, roller 13 moves toward the roller or cooperative squeezing element 14 along an arcuate path, which path is above and independent of the mop guard rails. The fact that the roller ends extend outwardly beyond the limits of the space defined by the mop guard rails, is a matter of considerable importance to the present invention.

In that form of the invention illustrated by Figs. 1 and 2, the mop guard rails in the region of the fixed squeezing element 14-15, are bent outwardly as at 26, and then rearwardly as at 27, to accommodate the length of the rollers or squeezing elements 14-15, whose working or pressing surfaces preferably are as extensive in length as that of the shiftable roller 13. The rearwardly directed offset portion 27 of each mop guard rail carries an upstanding perforated bracket 28, the perforations 29 and 30 of which provide bearings for the shaft ends 31 and 32 of the rollers 14 and 15, respectively. The upstanding bracket may be riveted, bolted, welded, or otherwise suitably fixed to the offset extensions 27 of the mop guard rails, or the complete mop guard rails with upstanding bracket may be of one-piece construction. The turned ends 24-24 of the mop guard rails may be made integral with the offset portions 27, if desired. The shafts of rollers 14 and 15 preferably are rotatable within the bearings 29 and 30, although it is of course possible to employ the equivalent construction consisting of fixing the shaft ends to the uprights 28 and permitting the rollers to rotate thereon. The mountings mentioned are clearly equivalent to one another, and are contemplated within the scope of the invention.

Attention is directed to the fact that the rollers or squeezing means 14-15 have their ends projected beyond the space limits defined by the major portion of the length of the mop guard rails, so that mop strands may not reach the axle ends of the rollers and become entangled or wound about the axles or other mountings during use of the device.

The container 4 may be furnished with a suitable bail or handle 33, which may preferably be furnished with a hand grip 34.

In that form of the invention illustrated by Fig. 3, the mop guard rails 121 and 122 are straight and equally spaced throughout their

length, except at the turned ends indicated at 123 and 124 corresponding with the ends 23 and 24 of Fig. 2. This modification illustrates also the use of but a single roller 114 as the cooperative squeezing element against which the shiftable roller applies its squeezing force. It should be understood that the assembly of Fig. 3 may be bodily substituted for the corresponding assembly illustrated by Fig. 2, the shiftable roller mounts, arms, and treadle being the same in each form of the invention.

With further reference to Fig. 3, it will be noted that the upstanding brackets 128 which rotatably support the roller 114, are of angle construction, or of substantially Z-shape, with one leg 129 fixed as by means of a bolt, rivet, welding or the like 130, to the mop guard rails adjacent their turned ends 124. The outer-most portions 123 of the brackets or uprights are disposed at a spaced relationship to one another such as exceeds the spacing between the substantially parallel mop guard rails 121 and 122. This construction results in accommodating the length of roller 114, which also exceeds the spacing between the mop guard rails. In this form of the device, the axle ends 131 of the roller are prevented from becoming entangled with the strands of any mop introduced into the wringer mechanism.

It is, of course, immaterial to the invention whether the turned ends 129 of the brackets be secured to the inner or outer faces of the mop guard rails, although the relationship illustrated by Fig. 3 is preferred since only one fastening device 130 need be employed in effecting a rigid mounting of a bracket to a mop guard rail.

As is obvious, the brackets 128 may be formed integrally with the mop guard rails, if desired, and such a structure is contemplated within the scope of the invention.

In addition to providing for free and unobstructed shifting of the moveable roller of the wringer toward and from the stationary squeezing element, the means of the present invention embrace the further advantage that the mop guard rails may be secured in spanning relationship to the inside of the container, at an elevation substantially level with the top of the container side wall. This materially strengthens the container, and so elevates the entire wringing assembly as to increase the fluid capacity of the container. Otherwise stated, the improved construction herein disclosed provides for disposition of the mop guard rails and the wringing elements well above the bottom of the container, so as to make available for the liquid contents thereof, a maximum amount of space within the container.

Finally, it will be observed that the manufacture and assembly of the parts utilized in the improved wringer structure, have been greatly simplified while at the same time rendered highly durable and effective for their intended purposes. The strands from a mop undergoing a wringing operation are, by the employment of highly simplified means, prevented from becoming entangled in any part of the operating mechanism of the wringer. The extreme simplicity of the mop guard rails and the mounts for the rollers is emphasized and clearly illustrated by the Fig. 3 drawing illustration.

In accordance with practice well-known in the art, the extension 6 may be riveted, bolted, or otherwise fixed to the body of the container, and spring 10 will have its inner end anchored to the

bracket 7 or to some other stationary part of the structure in the region of pivot 8.

In the broader aspect of the invention, the mop wringing assembly, exclusive of the container, is an apparatus complete in itself, and accordingly may be applied to a support or frame other than a container. For example, instead of the container providing the supporting medium for the mop wringing assembly, a suitable support might comprise simply an open frame properly designed to accommodate the wringer assembly, and preferably elevated sufficiently to permit any desired form of receptacle to be placed beneath it for catching the liquid wrung from a mop or the like. In such a construction, the wringing assembly is not necessarily fixed to the receptacle, or in any manner connected thereto. In reading certain of the claims, therefore, reference to a support or chassis for the wringer assembly does not imply any restriction to a bucket or other container.

It is to be understood that various modifications and changes may be made in the structural details of the device within the scope of the appended claim, without departing from the spirit of the invention.

What is claimed is:

A mop wringing apparatus for attachment to a pail, comprising in combination: a shiftable squeezing roller having a pressing area, and a cooperative squeezing roller likewise having a

pressing area, the rollers being of equal length and each including axle stubs extending from opposite ends of each roller, a pair of mop guard rails in the form of bent metallic straps, each having a straight intermediate portion and a pair of angular mounting ears at opposite ends thereof for attachment of the rails in spanning relationship to the pail, with said straight portions spaced apart a lesser distance than the length of the roller pressing areas, each of said rails having one of its ends provided with a substantially right angular outward bend and an adjacent rearward bend, to adapt the rails for accommodating between them the length of the second-mentioned cooperative squeezing roller, bearing means on each rail adjacent to said rearward bend for rotatably supporting the axle stubs of the cooperative squeezing roller and disposing the roller end peripheries in proximity with the outwardly bent portions of the rails, to avoid entanglement of mop strands with the axle stubs of the roller so supported, and means mounting the shiftable squeezing roller for bodily movement arcuately toward and from the cooperative roller above the straight portions of the rails, with the axle stubs and marginal peripheral portions of the shiftable roller disposed outwardly of both rails.
